UNITED STATES PATENT OFFICE

HARRY F. DUNCAN, OF CHEVY CHASE, AND GEORGE E. STONE, OF BALTIMORE,
MARYLAND

DESIGN FOR A BUILDING

Application filed April 8, 1931. Serial No. 39,402. Term of patent 14 years.

To all whom it may concern:

Be it known that we, HARRY F. DUNCAN and GEORGE E. STONE, citizens of the United States, and residing, respectively, at Chevy Chase, in the county of Montgomery and State of Maryland, and at Baltimore, in the county of Baltimore and State of Maryland, have invented a new, original, and ornamental Design for a Building, of which the following is a specification, reference being

had to the accompanying drawings forming part hereof, in which

Fig. 1 is a front elevation of the building, and

Fig. 2 is a side elevation thereof.

We claim:

The ornamental design for a building, as shown.

HARRY F. DUNCAN.
GEO. E. STONE.
